Armstrong & King

Grain Minnower

Patented Dec. 1, 1834.

Dec. 2. 1834

230

Martin, A. Armstrong & William H. Flury
Petitors Patent

The Schedule referred to in these Petitors Patent and, markings, part of the same containing a description in the words of the said Martin A. Armstrong & William H. Flury themselves of their improvement in machinery for sifting, cleaning and screening grain and berries of all kinds. To all to whom these presents shall come - Be it known that we Martin A. Armstrong & William H. Flury being both of the City and County of New York and State of New York have jointly invented a new and useful improvement in machinery for sifting, cleaning and screening grain & berries of all kinds & descriptions whatsoever, to the same whole or ground and that the following is a full and exact description of the construction and operation of the said machinery as invented and improved by us the said Martin A. Armstrong & William H. Flury. The Invention and Improvement aforesaid for the purpose aforesaid is two fold to wit. In the first place the said invention & improvement embraces and consists of a cylindric sifter formed & constructed in the manner following. that is to say. a cylinder is formed covered & bounded on its circular surface or boundary by wire or other, not wire or metal, of such strength construction and proportions as may be required by the particular kind or description of grain or berries to be sifted, cleaned, or screened. This cylinder is divided into two apartments by similar net works of like strength, construction and proportions placed & being in a cylindric form, within and parallel to the said outer covering, or boundary, and forming a smaller cylindric apartment within the larger or outer apartment. The said net work is in both instances secured, guaranteed & strengthened by bars of wood or metal placed & being lengthways with the said cylinder and, at both ends being affixed and secured to sides or facets of wood or metal which project the one over

Drawing (See back side)

236.

ed. of the said outer net-work respectively & to which said the said outer
 work is secured. One extremity, or end of the said outer outer apart-
 ment of the said cylinder is closed and bounded by a circular
 end plate of, wood or metal of the same diameter of the said
 cylinder thinnest affixed and secured from the middle of which
 said end plate a circular piece is cut out of sufficient size or di-
 mensions, to leave entirely open the end or extremity of the said inner
 apartment of the said cylinder. The said end plate is strengthened
 and guarded and secured by two arms of wood or metal crossing
 each other at right angles, at the center of the said end plate
 where they are secured in a journal or bearing of wood or metal
 and which arms run and extend at both ends thereof, respect-
 ively to the circumference of the said end plate. Between
 the said end plate and the said rim or felly which protects
 the said end edge of the said outer net-work as aforesaid
 a narrow open space is left all round the said cylinder
 except where the said bars run from the said last named rim
 or felly to the said end plate. The other extremity or end of
 the said cylinder is open except so much thereof as is covered by
 a narrow projecting rim of wood or metal which is affixed
 and secured to the said rim or felly which protects that end
 edge of the said outer net-work as aforesaid. The said project-
 ing rim projects inwards from the said outer boundary of the
 said cylinder and is sufficiently wide to prevent any grain or
 corns from passing or falling from the said outer apartment of the
 said cylinder at that end thereof. At a short distance within the
 said projecting rim two arms of wood or metal are placed
 which arms cross each other at right angles at the center of
 a circle whose circumference is on the concave surface of the
 said cylinder and are there secured in a journal or bearing
 of wood or metal and which arms at both ends thereof
 respectively run and extend and are secured to the said
 rim or felly, which at that end of the said cylinder, is

jects, the end edge, of the said, outer network, as aforesaid. The said inner apartment of the said cylinder is occupied by a fan composed of a shaft to which are affixed and secured at intervals, eight angles to each other four thin plates of wood or metal of such length and depth as will permit them to revolve, both and upon the said shaft freely, and with as much effect as may be within the said inner apartment of the said cylinder. The said cylinder is attached to, and supported by an oblong frame of wood or metal consisting of four legs, sufficiently secured together by single cross members on each of the sides thereof and by double or parallel cross bars on each side of the ends thereof respectively; with this frame the said cylinder is joined connected & attached on the said open end of the said cylinder by a short solid round shaft of wood or metal which passes through and revolves freely within a sufficient bearing and journal in an inner cross bar on one end of the said frame and is firmly secured to the said journal or bearing of the said arms within that end of the said cylinder aforesaid; and on the other or close end of the said cylinder by a short round shaft which is firmly affixed and secured to the said journal or bearing of the said arms of that end of the said cylinder and which shaft passes through and freely revolves within a sufficient journal in an inner cross bar of that end of the said frame. Through the middle of the last named shaft is a round hole or bore of sufficient diameter to allow the said shaft of the said fan to work or revolve freely within it. Affixed and secured to the said frame as close as convenient above the said open end of the said cylinder is a sufficient hopper made of wood or metal to the bottom of which hopper is affixed & secured a board or conductor of wood or metal which conducts and leads from the opening in the bottom of the said hopper and inclines gradually toward the said the said open end of the said cylinder.

The lower end of the said conductor or leader rests in the space between the aforesaid projecting rim (which prevents grain or berries from passing off at that end as aforesaid) and the said arms which are affixed to the said cylinder at a short distance within the said projecting rim as aforesaid, so that the said cylinder can revolve freely without being interrupted, stopped or touched by the said leader or conductor, and so also that grain or berries falling from the said conductor or leader fall upon & against the lower part of the inner surface of the said outer net-work & within the said projecting rim. The said legs of the said frame at that end thereof where is the said open end of the said cylinder are as much longer than the said other legs thereof as is sufficient to incline the said cylinder from the said open end thereof to the said close end thereof in such a degree as will cause grain or berries when in the said outer apartment of the said cylinder to descend gradually with the motion of the said cylinder from the said open to the said close end of the said outer apartment thereof. A receiver is affixed and secured to the said frame under the said cylinder which receiver gradually inclines towards and terminates in a conductor or leader at mouth or other opening.

Directly under the said narrow open space left as aforesaid round the said cylinder at the said close end thereof, is affixed and secured another smaller receiver wholly separated from the said first-mentioned receiver and descending and inclining to a point where it terminates in a leader or conductor which inclines towards and beyond that end of the said frame. Below the said two receivers and suspended early a leader and parallel to the aforementioned short shafts of the said cylinder a shaft called the lower shaft passes through and connects freely with the several round bands in the lower neighborhood.

of the said ends of the said frame, and to wheels lower shaft between the bearings thereof at each end of the said frame (or
specially) are affixed, and secured two round pulleys of wood
or metal of unequal diameters, the smaller thereof being at that
end of the said frame where is the said open end of the said
cylinder and the larger thereof at that end of the said frame
where is the said close end of the said cylinder. The proportion
between the diameters of these lower pulleys must be reg-
ulated by the intended velocity with which it is desired to im-
pact to the said frame. The said cylinder is worked or
set in motion by a screw (or other power, which may be
applied) attached to the said short solid shaft of the said
cylinder or such power may be applied to the said other
short shaft of the said cylinder or to the said lower shaft.

To the said short solid shaft of the said cylinder
between the bearings thereof in the said double or para-
llel cage has a round pulley of wood or metal is affixed
and secured directly over the said smaller pulley of the
said lower shaft and is as much longer in diameter
than the last named pulley as the increased velocity de-
sired to be given to the said frame may require. The said up-
per pulley is connected with and acts upon the said small
er pulley of the said lower shaft by means of a connecting
strap which when the cage (or other power aforesaid)
turns the said upper pulley, acts upon & turns the said
lower pulley in the same direction, and with as much
greater velocity as the difference between the diam-
eters of the said pulleys will cause. On the other end
of the said lower shaft, the said larger pulley, shaft of
fixed, necessarily revolves with the same velocity as the
said smaller pulley last described, and by means of a connect-
ing strap is connected with and acts upon a smaller
pulley (affixed and secured to the said shaft of the said frame)

directly above the said larger pulley of the said lower shaft, the difference in diameter between the said two last named pulleys must also be regulated by the increased velocity which it is desired to impart to the said fan —

The said shaft of the said fan is set in motion by and revolves with the said pulley thereto affixed as aforesaid and passes out through and revolution within the aforesaid box in the said shaft of the said cylinder at ^{end} start ^a thereof having its own journal and bearing on an outer cross bar at that end of the said frame and at its opposite extremity rests upon and revolves freely with in a bearing in the inner end of the said shaft solid shaft, which then supports the said cylinder and connects it with the said frame as aforesaid. The said connecting strap last aforesaid is offset between the said pulleys which it connects as aforesaid so that thereby the motion given to the said fan is opposite to the motion given to the said cylinder as aforesaid, the revolutions of the said fan being directly reverse to those of the said cylinder. The said fan moves with a much greater velocity than the said cylinder as the relative differences between the diameters of the said pulleys will cause as aforesaid. The motions aforesaid may also be obtained by connecting rods or cog-wheels set in the place & stead of the aforesaid pulleys and connecting straps or by connecting the said cylinder with a pulley on the said lower shaft by means of a connecting strap or connecting rod. Glass or beads being placed on the said upper part of the said lower shaft or conductor then to affixed, and held in aforesaid against and upon the said inner surface of the said outer jacket of the said cylinder in the said cylinder. They are prevented from falling from a passing out of the said open end of the said outer jacket by the aforesaid projections, viz. The said

cylinder being put in rapid motion in pinions aforesaid the said grain or berries are necessarily kept in rapid and continuous motion against & upon the said fan since surface of the said outer net-work of the said cylinder and the said fan at the same time revolving in the opposite direction with much greater velocity forced and draws a strong current of air against the said grain or berries and continually in a manner oppose and resist the motion given to them by the said cylinder. By this means the said grain or berries are speedily sifted, cleaned and screened off from all impurities sufficiently small to pass through the openings in the said outer net-work whence the said impurities fall into the said larger receiver & pass off and are discharged at the said mouth or outlet opening, thence and the said grain or berries gradually passing down the inclined inner surface of the said outer net-work to the close end of the said outer apartment, fall through the aforementioned narrow open space then left round the said cylinder as aforesaid into the said smaller receiver below and under the same as aforesaid whence they pass off by & through the said leader or conductor (hence leading or conducting) as aforesaid. When such grain & berries so to be sifted cleaned and screened are heated the aforementioned rapid motion of the said cylinder and the said current of air do thicken against the said grain and berries as aforesaid speedily cool the same, and when such grain and berries are ground & have become caked or hardened by wet or otherwise the said motion and air speedily break such cakes & reduce such hardens and restore such grain and berries to their proper state as ground grain & berries. A moveable cap or cover may be placed over the said cylinder for the purpose of protecting and covering the same from dust dirt or moisture. They see the said Master J. Armstrong & William G. H. King say and claim that the aforesaid joint & original invention of the cylinder herein before mentioned & described for the purpose of

hence before mentioned and described and of the application & use as herein before stated and set forth of all the machinery herein before mentioned and described for the purposes aforesaid.

In the second place the said invention & improvement embraces & consists of a separator made of wood or metal and which is of the usual form of a sieve, except that the bottom thereof may be either solid or perforated like that of a sieve or have the outer part thereof perforated like a sieve and the inner or middle part thereof solid and except also the openings or passages theron herein after particularly mentioned and described. In the projecting view of the said separator and on a level with the bottom thereof or in the bottom plate of the said separator and close to the said projecting view thereof are one or more openings continued by leaders or conductors on the outside of the said separator into which leaders or conductors fit, small slides which close or lessen the passages therethrough perfectly at pleasure. The number of the said last named openings must be regulated by the size and capacity of the separator used. There is also another opening in the middle of the said bottom plate, which opening is circular, the center thereof being the centre of the said bottom plate, to the latter (name opening) both above and below fits loosely a thin plate of wood or metal of greater diameter than the said opening and each of which plates has a smaller opening or passage in the middle thereof, respectively also circular. These latter named openings or passages are connected together by a hollowed or bored piece of wood or metal passing through the said opening in the middle of the said bottom plate and secured to the said openings in the said thin plates so that one thereof fits loosely but closely above or on and the other thereof fits loosely but closely below or under the said bottom plate of the said separator and so as to cover the said opening in the said bottom plate last aforesaid, except

43342

except so much thereof as is equal to and occupied by the passage in the said hollowed or bored piece or pipe. The said hollowed or bored piece or pipe rises above the bottom of the said separator to a small height more or less, as may be required by the size or capacity of the separator to which it is attached and of which it forms a part and of the shape and form of a common funnel the inverted conical part or mouth thereof being above and the pipe thereof being, as aforesaid below the level of the bottom of the said separator. The said separator rests on stones so as to be removed at pleasure upon three equal crooked poles and being in a frame of wood or metal and at the respective ends of an equilateral triangle. These last named crooked stands or rests in steps or bearings in the lower part or platform of the said frame last named, wherein the lower ends thereof work or revolve freely. The shafts of the said three crooked rods or rebolos freely in sufficient journals in the said frame and the said shafts work freely in equidistant journals in the said bottom plate of the said separator. The said three crooks may be constructed so that their sweep may be lengthened or diminished by means of a slot-way, and moveable pin in each of the arms thereof, respectively. The sweep of the said three crooks must be regulated that the capacity of the aforesaid three levers or conductors from the said smaller receiver below and under the narrow open space round the said cylinder as aforesaid shall always during the motion of the said separator turn after described over some point, or on the said bottom plate of the said separator between the said projecting rods thereof and the said moveable center piece thereof herein before mentioned and described. The said frame of the said separator is affixed and secured to the said frame of the said cylinder at the close end thereof under the said three levers or conductors which project from the said small receiver beyond that end of the said cylinder and passes

as aforesaid. On the supporting cranks of the said separator and to the shaft thereof is affixed and secured a said cog wheel corresponding to and joining同一之機械 connected and locked with another said cog wheel affixed and secured to that end of the said lower shaft without, and beyond the bearings thereof. Thus when the said lower shaft is in motion as aforesaid. The last named cog wheel therunto attached sets in motion the corresponding cog wheel on the said supporting crank of the said separator as aforesaid; and the said last named crank thus set in revolution propels and forces the said separator so that it points at the centre of the said bottom plate thereof, performs a circle round a point equidistant from the said corners of the said equilateral triangle with a radius equal to each of the arms of the said supporting cranks; and when the said separator is put in motion as aforesaid the said moveable centre piece thereof, aforesaid is continually thrown towards that point on the edge of the said bottom plate of the said separator farthest from the said point, equidistant as aforesaid from the said corners of the said equilateral triangle. --

When grain or berries pass from the said inclined conductor or leader connecting or leading from the said smaller receiver as aforesaid. They fall upon the bottom plate of the said separator between the said projecting arm thereof and the said moveable centre piece thereof. By the laws of con-
tinuous motion, and of gravity, grain or berries being of greater specific gravity than impurities, mix'd with them are thrown by the aforesaid motion of the said separator towards or against the said projecting arm thereof, whence they gradually pass off and are discharged through a passage or passage and leader or conductor or leaders or conductors in or close to the said projecting arm as aforesaid. Impurities mix'd with grain or berries being of less specific gravity than the said grain or berries as aforesaid gradually

gradually accumulate around the said movable centre piece
spoon and into the mouth thereof, aforesaid and fall and be
discharged through the said movable centre piece as aforesaid.

Whatever tendency (if any) grain or berries might have
on first falling on the said separator to pass to, or into, the
said passage of the said movable centre piece, is sufficiently
resisted by the raised side of the said funnel or centre piece
until such grain or berries are thrown as aforesaid (towards
or against) the said projecting rim of the said separator.

When grain or berries happen to be of less specific gravity
than impurities mixed with them the operation of the said
separator is necessarily reverse to the operation thereof herein
before described: the said grain or berries gradually falling
off through the said centre piece and the said impurities
through the said passage or passages in or close to the said
projecting rim as aforesaid. and when grain or berries happen
to be of less specific gravity than certain impurities mixed
with them and of greater specific gravity than certain other
impurities also mixed with them, then the said impuri-
ties are separated from said grain or berries, by passing the
said grain and berries twice through the said separator as
aforesaid by the means aforesaid. The particles of mat-
ter in or on the said separator near the said funnel or
centre piece are kept by the aforesaid motion of the said sep-
arator in continual motion around the centre of the said
bottom plate of the said separator. The said funnel or centre
piece is constructed and placed as aforesaid so as to receive
or take a similar or corresponding motion as aforesaid, and that
the said motion of the said particles is not, further, interrup-
ted or disturbed by the said funnel or centre piece. But
the said funnel or centre piece may also be constructed
and placed stationary and fixed at the centre of the said
bottom plate of the said separator and will thus also answer the

146
the purposes aforesaid. If the said bottom plate or part there-
of is perforated or made of net or sieve work as aforesaid any
small dust or impurity which may out, pass away otherwise
as aforesaid, will escape and be discharged through such net
or sieve work or perforations. Thus dirt or other impurities
which pass or escape with grain or berries from the said cylinder
is separated therefrom by the aforesaid operation of the said
separator. The aforesaid motion of the said separator may also
be obtained by means of a connecting shaft connecting a round
pulley affixed and secured to one of the said three supporting
cranks of the said separator and a pulley affixed and secu-
red to the lower of the shafts aforesaid or by means of a con-
necting rod, one extremity of which should be affixed to
the said separator, and the other extremity to a crank or pulley
affixed and secured to one of the shafts aforesaid; whereby
the last named extremity of the said connecting rod would
be carried round by the said crank or pulley describing
a circle or an imaginary perpendicular plane, and the other
extremity thereof would describe a circle or an imagi-
nary horizontal plane, carrying with it the said separator.
When desirable, two, three or more separators may be used
in the manner following, to wit, to the shafts of two of the
said supporting cranks (to which is not attached the said
pulley or other pulley for the purposes aforesaid) round pulleys
may be affixed and secured, connected by connecting shafts
with similar pulleys similarly affixed and secured to a
supporting crank of each of two similar separators respect-
ively, and these additional separators may in like man-
ner be connected with other similar separators. In this last
named case of having more than one separator as aforesaid
the said leader or conductor, leading or conducting, as aforesaid
from the said smaller receiver, should branch off in as
many separators branched as separator used, and such bran-
ches

433 1/2

214

ches should conduct grain or beans, equally, to such separator, in like manner as is herein before mentioned, set forth and described; the said separator may be covered by a moveable plate or cover with a sufficient passage for grain and beans.

And now the said Martin & Armstrong & William H. St. King, do say and claim that we are the joint and original inventors of the said entire pieces of the said separator as is herein before particularly described for the purposes aforesaid and of the application and use of it herein before stated and set forth of the machinery herein before in the second place mentioned and described for the purposes aforesaid. The said cylindrical sifters and the said separator may also be respectively used in the manner aforesaid for the purposes aforesaid separately and apart. And we the said Martin & Armstrong & William H. St. King have herunto annexed two views or drawings of the machinery invention & improvement herein before mentioned and described, as and for a part and parcel of this our specification, thereof: one of the views or drawings marked N° 1. (number one) being a front or full view of the side of the said cylinder, separator and other machinery; and the other of the said views or drawings marked N° 2. (number two) being an oblique view or drawing of the open end or extremity of the said cylinder. And we the said Martin & Armstrong & William H. St. King, have therunto respect-
ively and to the several parts thereof, respectively, annexed certain letters as and for letters or marks of reference to sufficient or indicate the several and respective parts of the said views or drawings to which they are so annexed in the following, ^{or description} explanation of the said views or drawings to wit: A. represents or indicates the hopper aforesaid. B. represents or indicates the feeder or conductor hence leading to conducting at aforesaid C. represents or indicates the

wire or other net-work or boundary aforesaid of the said outer apartment of the cylinder aforesaid D represents or indicates the aforesaid bars to which the last named net-work is secured as aforesaid. E represents or indicates the arms or felloes which protect the end edges of the net-work within described respectively as aforesaid. F represents or indicates the arms aforesaid crossing each other at right angles at or near the respective ends of the said cylinder as aforesaid. G represents or indicates the journals or bearings in which the said arms are secured as aforesaid. H represents or indicates the wire or other net-work or boundary of the aforesaid inner apartment of the said cylinder I represents or indicates the fan aforesaid. K represents or indicates the aforesaid shaft of the said fan. L represents or indicates the aforesaid short shaft of the said cylinder placed and being at the close end thereof as herein before described. M represents or indicates the aforesaid narrow open space left all round the said cylinder at the close end thereof as herein before described. N represents or indicates the aforesaid bar to which is secured the said net-work of the said inner apartment of the said cylinder as aforesaid. O represents or indicates the aforesaid crank attached to the said short solid shaft of the said cylinder as aforesaid P represents or indicates the aforesaid short solid shaft of the said cylinder placed and being at the open end thereof as herein before described. Q represents or indicates the open end bars of the frame aforesaid to which the said cylinder is attached as aforesaid. R represents or indicates the open ends of the said frame. S represents or indicates the open end fully applied and secured to the said short solid shafts of the said cylinder between the bearings thereof as herein before described. T represents or indicates the aforesaid shorter part of the said long shaft. U represents or indicates the aforesaid cage

larger pulley of the said lower shaft. V represents or indicates the aforesaid pulley affixed and secured to the said shaft of the said fan as aforesaid. W represents or indicates the aforesaid connecting strap which connects the said pulley of the said shaft with the said smaller pulley of the said lower shaft as aforesaid. X represents or indicates the aforesaid connecting strap which connects the said larger pulley of the said lower shaft with the said smaller pulley affixed and secured to the said shaft of the said fan as aforesaid. Y represents or indicates the aforesaid larger receiver placed and being under the said cylinder as aforesaid. Z represents or indicates the aforesaid mouth or ^{other} opening thereof. a. represents or indicates the aforesaid smaller receiver placed and being under the said narrow open space at the other end of the said cylinder as aforesaid. b. represents or indicates the aforesaid leader or conductor thence leading or conducting as aforesaid. c. represents or indicates the aforesaid lower shaft. d. represents or indicates the aforesaid projecting rim of the said separator. e. represents or indicates one of the aforesaid leaders or conductors leading or conducting from one of the aforesaid openings or passages in or close to the said projecting rim as aforesaid. f. represents or indicates the small slide which slides or opens the passage of the said leader or conductor as aforesaid. g. represents or indicates the aforesaid moveable funnel, center piece or passage of the said separator. h. represents or indicates the aforesaid suspending cranks of the said separator. i. represents the aforesaid milled cog-wheel affixed to the end of the said lower shaft as aforesaid. j. represents or indicates the aforesaid corresponding milled cog-wheel affixed to one of the said suspending cranks as aforesaid. k. represents or indicates the aforesaid small pulley, which may be affixed as aforesaid to one of the said suspending cranks of the said separator for the

12/2/1834 8522 1/2X

230.

purposes aforesaid. L. represents or indicates the connecting strap connecting the last named fully with another fully as aforesaid for the purposes aforesaid. M. represents or indicates the aforesaid frame of the said separator. N. represents or indicates the aforesaid narrow projecting rim projecting inwards around the said open end of the said cylinder as aforesaid.
